CLAIM

The ornamental design for a vehicle article carrier bracket, as shown and described.

DESCRIPTION

FIG. 1 is a perspective view of a vehicle article carrier bracket showing my new design, with the bracket shown inserted in a slot on a vehicle rooftop;

FIG. 2 is an enlarged perspective view thereof;

FIG. 3 is an enlarged top view thereof;

FIG. 4 is an enlarged left side view thereof;

FIG. 5 is an enlarged front view thereof;

FIG. 6 is an enlarged right side view thereof; and,

FIG. 7 is an enlarged rear view thereof.

The broken line showing of environment in FIG. 1 is for illustrative purposes only and forms no part of the claimed design.
